Attorney

UNITED STATES PATENT OFFICE.

VICTOR HUGO FRIER, OF WAKONDA, SOUTH DAKOTA.

POST-PULLER.

1,373,609.

Specification of Letters Patent.

Patented Apr. 5, 1921.

Application filed July 14, 1920. Serial No. 396,148.

To all whom it may concern:

Be it known that I, VICTOR H. FRIER, a citizen of the United States, residing at Wakonda, in the county of Clay and State 5 of South Dakota, have invented certain new and useful Improvements in Post-Pullers, of which the following is a specification, reference being had to the accompanying drawings.

- 10 This invention relates to improvements in post pullers.
An important object of the invention is to provide an extremely simple and efficient apparatus for pulling posts from the ground 15 without breaking or otherwise injuring the posts. To this end my invention consists in a relatively large drum adapted to be positioned adjacent the posts to be pulled and provided with means preventing its movement away from the post. About this drum a cable may be passed and attached to the post at or adjacent the ground and by pulling in the cable the post may be moved vertically without injury thereto.
20 In the accompanying drawings, wherein for the purpose of illustration is shown a preferred embodiment of my invention and wherein like reference characters designate like parts throughout:
25 Figure 1 is a side elevation of my device in use for removing a post from the ground, and

Fig. 2 is a top plan view thereof.

Referring now more particularly to the 30 drawings, the numeral 10 indicates a drum or pulley having a hub portion 11 and spokes 12, the hub portion 11 being provided with the usual center aperture within which is mounted a shaft 13. The ends of this shaft 35 are formed with eyes 14 in one of which is secured one end of a chain 15. The eye upon the opposite end of the shaft is provided with any suitable means 16 whereby the free end of the chain 15 may be adjustably secured thereto.

In the use of my device the drum 10, which is preferably about 30 inches in diameter and at least 18" wide and slightly transversely concaved upon its periphery, 40 is positioned adjacent the post 17 and the chain 15 passed thereabout and secured by the securing means 16 to the eye upon the opposite end of the shaft. A cable 18 is then

secured to the post adjacent the ground and passed over the drum 10. A draft animal 55 may be secured to the free end of the cable 18, and upon pull being exerted upon the cable the post 17 is approximately vertically shifted and accordingly withdrawn from the ground. It will be understood that as the 60 cable 18 is tightened the chain 15 tightens upon the post as the base elevates the drum, due to the change in position of the chain as drawn somewhat closer to the post, causing the pull upon the post to become more 65 nearly vertical as the movement progresses.

It will be understood that I do not limit myself to the particular construction of pulley or drum hereinbefore set forth, nor to the peculiar securing means described, as these constructions are capable of varied 70 changes, obvious in character, and I accordingly may make any such changes without departing from the spirit of the invention of the scope of the subjoined claims.

Having now described my invention, what 75 I claim is:

1. In a post puller a drum pulley embodying the usual apertured hub, a shaft extending through the aperture of the hub, a flexible element adapted to be passed about the post and having one end secured to one end of said shaft, means for adjustably securing the free end of said flexible element to the other end of said shaft and a flexible element extending over said drum and adapted 80 to be secured to the post adjacent the ground.

2. In a post puller a drum pulley having its peripheral surface transversely concaved and embodying the usual apertured hub, a shaft extending through the aperture of the 90 hub, a flexible element adapted to be passed about the post and having its ends secured to the ends of said shaft, and a flexible element extending over said drum and adapted to be secured to the post adjacent the ground.

3. In a post puller a drum pulley embodying the usual apertured hub, a shaft extending through the aperture of the hub and provided upon the ends thereof with an eye, a flexible element adapted to be passed about the post and having one end thereof secured 100 to the eye at one end of said shaft, means for adjustably securing the free end of said flexible element carried by the eye at the other end of said shaft and a flexible element ex-

tending over said drum and adapted to be secured to the post adjacent the ground.

4. In a post puller a drum pulley having its peripheral surface transversely concaved and embodying the usual apertured hub, a shaft extending through the aperture of the hub and provided upon the ends thereof with an eye, a flexible element adapted to be

passed about the post and having its ends secured to the eyes of the ends of said shaft, **10** and a flexible element extending over said drum and adapted to be secured to the post adjacent the ground.

In testimony whereof I hereunto affix my signature.

VICTOR HUGO FRIER.
